UNITED STATES PATENT OFFICE.

JOEL JENKINS, OF MONTCLAIR, NEW JERSEY.

CUFF-HOLDER.

SPECIFICATION forming part of Letters Patent No. 729,768, dated June 2, 1903.

Application filed August 18, 1902. Serial No. 120,054. (No model.)

To all whom it may concern:

Be it known that I, JOEL JENKINS, a citizen of the United States, residing at Montclair, county of Essex, and State of New Jersey, 5 have invented a new and useful Improvement in Cuff-Holders, of which the following is a specification.

My invention relates to an improvement in cuff-holders which are used to adjustably attach the cuff to the shirt-sleeve.

The invention contemplates a construction which may be readily attached to and detached from said cuff, but which will remain securely in position until detached by the 15 wearer.

My invention is illustrated in the accompanying drawings, in which—

Figure 1 is an elevation of my complete cuff-holder. Fig. 2 is a side view of the end 20 which engages the cuff. Fig. 3 is a sectional view of the same. Fig. 4 is an end view of the device.

The cuff-holder A is provided at one end with the cuff-holding portion proper, B, and 25 at the opposite end with a clip D for engagement with the sleeve of the shirt. Any practical form of clip may be used with this holder, if desired, without altering the character of my invention as set forth in this application.

30 The form of clip shown, however, consists of the jaws d and d', hinged together at d², the jaw d' having pivoted at d² a latch d³, said latch having a finger-piece d⁵, by which it may be manipulated to lock and unlock the jaws 35 d and d'. The shank A may be made integral with either of the members d or d'.

In constructing my cuff-holder a blank is struck up from sheet metal having integral therewith, if desired, one member of the clip 40 D, as shown. The opposite extremity of the blank is bent to the form of hook shown in Figs. 2 and 3, having the tongue B with an outwardly-turned extremity b. Adjacent to the bight of the hook is a projection C, which 45 may extend slightly beyond the bight of the hook, substantially parallel and in a plane with the shank A of the hook. This projection C forms a stop which prevents the

shank A from slipping through the button-hole of the cuff, thus allowing the cuff to run 50 back on the holder and become displaced. In practice the buttonholes of the cuff-band engage the bight of the hook and rest in the V-shaped opening E between said hook and the projection C. The holder is readily engaged with the cuff by slipping the tip b of the tongue B through the buttonholes of the cuff and drawing the same therethrough until arrested by the projection C.

Having now described my invention, what 60 I claim, and desire to secure by Letters Patent is—

1. In a cuff-holder, a shank; means for engaging the shirt-sleeve at one extremity of said shank; a hook having its tongue bent 65 back over said shank for engaging the cuff at the opposite extremity of said shank; and a projection substantially parallel and in a plane with said shank for holding the cuff in engagement with the bight of said hook. 70

2. In a cuff-holder, a shank, means at one extremity thereof for engaging a shirt-sleeve, the opposite end of the said shank bent back upon itself to form a hook, and a projection adjacent to said hook substantially parallel 75 and in a plane with said shank.

3. In a cuff-holder, a shank, means at one extremity thereof to engage a shirt-sleeve, a hook at the opposite end thereof, said hook having its tongue bent back upon the shank 80 and a projection adjacent the bend of the hook substantially parallel and in a plane with said shank and extending beyond the bight of the hook.

4. In a cuff-holder, a shank provided with 85 means to engage the shirt-sleeve, one extremity of said shank bent back upon itself to form a hook, and a projection adjacent to the bend of said hook substantially parallel and in a plane with said shank to form a stop. 90

In testimony whereof I have hereunto set my hand this the 12th day of August, 1902.

JOEL JENKINS.
